FLIER CONSTRUCTION

Michael J. McHale, Scranton, Pa.

Application August 16, 1946, Serial No. 691,103

14 Claims. (Cl. 57—116)

1

My invention relates to fliers of the type used with spinning machines, and more particularly to a flier block arrangement having improved means for attaching and supporting the flier wires.

In Patent 2,187,862, issued to me January 23, 1940, there is disclosed a flier construction having a flier wire support member in the form of a plate adapted to fit over the head portion of the flier body or block, the plates being attached to the flier body by means of a cap positioned below the plate and attached thereto by spot welding; also in Patent 2,212,299 issued to me August 20, 1940, there is disclosed a flier construction for a bi-partite flier wire support member in the form of complementary sections having semi-circular cut-out portions adapted to seat in a peripheral groove at opposite sides of the flier block. The arms, defined by the cut-out portions, are adapted to overlap and means are provided for engagement with the peripheral flanges of the block whereby the sections of the flier wire support are securely clamped or locked to the flier block.

The present invention relates to a flier of the type disclosed in the aforementioned patents and particularly to an improved form of flier wire support member, together with means for attaching the support to the flier block. After considerable research and experimentation, I have found that the construction of my prior patents can be substantially simplified to provide improved operation and with marked economies in manufacture.

An object of my invention is to provide a flier block having improved means for attaching and supporting the flier wires thereon.

Another object of my invention is to provide a flier construction having means whereby the arms of the flier wires are supported in a fixed plane in the vicinity of their points of attachment to the flier block.

Another object of my invention is to provide an improved flier construction wherein the flier wires are attached to the flier block by twisting or entwining the arms thereof, portions of the arms beyond the points of attachment being supported in a fixed plane whereby undesirable flexing of the flier wires about their points of support is prevented.

With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the appended claims.

In order to make my invention more clearly understood, I have shown in the accompanying drawings means for carrying the same into practical effect, without limiting the improve-

2

ments in their useful applications to the particular constructions, which for the purpose of explanation, have been made the subject of illustration.

5 In the drawings:

Figure 1 is an elevational view, partly in section, showing my improved flier in operative position on a bobbin spindle.

Fig. 2 is a plan view of the flier shown in Fig. 1.

Fig. 3 is a perspective view of the flier block shown in Fig. 1.

Fig. 4 is a plan view of the bottom of the flier shown in Fig. 1.

Fig. 5 is a plan view of a modified form of flier.

Fig. 6 is a perspective view of the flier block used with the flier shown in Fig. 5.

Fig. 7 is a bottom plan view of the flier shown in Fig. 5.

Fig. 8 is a plan view of another modified form of flier adapted for use with the block shown in Fig. 3; and

Fig. 9 is a bottom plan view of the flier shown in Fig. 8.

The improved construction of the present invention comprises essentially a flier block in the form of a centrally apertured body member having base and head portions, a frusto-conical peripheral flier wire support member formed on the body between the base and the head portions, and a flier wire support adapted to seat on the peripheral edge of the upper base of the frustum. The flier wire support member, which may be formed from metal or other suitable material, is provided with a central opening adapted to receive the head portion of the block. In order to securely lock or clamp the flier wire support to the block, the body portion of the support contiguous to the central opening is formed with slits which define tongue members adapted for engagement with the body of the block when the plate is seated in operative position on the flier block. The flier wire support is further provided with flier wire retaining means, the support and block cooperating to securely maintain the flier wires in desirable operative position.

Referring to the drawings, and more particularly to Fig. 1, there is shown a flier arrangement associated with a bobbin 1, mounted in operative position on a suitable spindle 2, of a conventional winding machine. The bobbin is provided with a head member 3, and a centrally recessed portion 4 adapted to receive a ferrule 5 having an aperture 6 through which the flier foot 7 is inserted in the flier block, designated generally by numeral 8, comprising a centrally apertured body portion 9 and a head portion 10. Between the base and the head portions, there is provided a peripheral flange 11 adapted to form a seat for the flier wire support member, as will be explained more fully hereinafter.

The peripheral flange of the flier block 8, reference being had to Fig. 3, is substantially in

the form of a frustum of a cone, the flat peripheral edge 12 of the upper base of the frustum forming a seat for the flier wire support. It will be noted that the surface of the peripheral flange 11 slopes uniformly upwardly to points just below the peripheral edge of the upper base of the frustum. In other words, the slope of the peripheral flange terminates at a line 13, the surface between this line and the peripheral edge of the upper base of the frustum being substantially vertical to provide a peripheral recess forming a seat for the central block engaging section of a flier wire.

Referring to Fig. 2, the flier wire support 14 is formed with a central opening adapted to receive the head of the flier block. The body portion of the support contiguous to the central opening is formed with a plurality of slits 15, defining tongue members 16 therebetween. In this embodiment of the invention, the flier wire support is in the form of a metal cap having depending skirt portions 17 (Fig. 4) formed with suitable notches adapted to receive the arms 18 of the flier wires. It will be noted that each of the flier wires is provided with a central block engaging portion 19, and that the arms are off-set or bent at 20 whereby the flier wires are securely clamped or locked within the slots formed in the depending skirt portions.

In assembling the flier, the flier wire support 14 is placed on the head portion 10 of the flier block and is forced downwardly so that the tongue members 16 are flexed or expanded upwardly into engagement with the surface of the head portion of the block, alternate portions 16' between successive tongues remaining in substantially the same plane as the body portion of the cap and being forced into tight engagement with the upper portion of the block. After the flier wire support is attached in operative position on the block, the flier wires are attached thereto, as shown in Fig. 4, the central block engaging sections 19 of the flier wire being seated in the shallow peripheral groove formed in the vicinity of the upper base of the frusto-conical peripheral flange.

By means of this arrangement, it has been found that the flier wire support, together with its associated flier wire attaching means, in co-operation with the frusto-conical shaped flange provides a secure support for the flier wires and prevents rotative movement of the support with respect to the block. The flier wire support can be easily and quickly applied to the block and after it is placed in the operative position, the tongue members securely grip the head of the block so that the support cannot move in any direction with respect thereto. The flier wires can also be quickly applied to or removed from the support, and when attached to the support, are maintained in the desired operative position whereby undesirable flexing of the flier wires about their points of support is prevented.

Referring to Fig. 5, the modified form of flier wire support 21 comprises a substantially rectangular shaped member, the free ends 22 of which are slotted and turned backwardly inwardly upon themselves to form flier wire attaching means, as shown in Fig. 7. In this arrangement, it will be noted that the body portion of the flier wire support is formed with grooves 23 adapted to receive the arms of the flier wires. In order to further assist in maintaining the arms in desired separated position, the support is formed with depressed portions 24.

The flier block (Fig. 6) designed for use with the modified form of support shown in Fig. 5, is substantially the same as the block shown in Fig. 3, however, differs therefrom in that its top or head portion is formed with a peripheral flange 25, defining a groove between said flange and the upper base of the frusto-conical shaped flange. In assembling the device shown in Fig. 5, the flier wire support is placed over the head of the block and is forced downwardly thereon. The ends of the tongues or fingers 16 seat in the groove 26, that is to say, rest against the under surface of flange 25, and are pressed into engagement with the body of the block. Simultaneously with the positioning of the tongues, the body portion of the support is indented or depressed at points 27, and forced into frictional engagement with the block.

By means of the above described arrangement, the flier wire support is securely attached to the flier block and rotative motion therebetween is prevented. As will be seen in Fig. 7, the flier wires overlap as at 28, and the arms of the wires are maintained in desired separated position by the grooves 23 and depressed portions 24.

Referring to Figs. 8 and 9, there is shown a modified form of flier wire support adapted for use with a flier block of the type shown in Fig. 3. In this arrangement, the support is attached to the block by means of fingers 33, which are forced inwardly against the upper head portion, whereby to lock the parts together.

While I have shown and described the preferred embodiment of my invention, I wish it to be understood that I do not confine myself to the precise details of construction herein set forth, by way of illustration, as it is apparent that many changes and variations may be made therein, by those that are skilled in the art, without departing from the spirit of the invention, or exceeding the scope of the appended claims.

What I claim is:

1. In a flier for spinning machines and the like, a central apertured body member having base and head portions, a peripheral flier wire support member formed on the body between the base and the head portions, a flier wire support adapted to seat on the peripheral member, said support having a central opening adapted to receive the head portion of the body member, and means integral with the flier wire support contiguous to said central opening and frictionally engaging the flier body when the flier wire support is seated on said peripheral member, whereby the flier wire support is securely clamped to the flier body.

2. In a flier for spinning machines and the like, a centrally apertured body member having base and head portions, a peripheral flier wire support member formed on the body between the base and head portions, a foot member on said body adapted for insertion into the head of a bobbin, a flier wire support adapted to seat on the peripheral member, comprising a cap having a body portion formed with a central opening adapted to receive the head portion of the body member and means integral with said cap contiguous to the central opening and frictionally engaging the flier body when said cap is seated in operative position on said peripheral member, whereby the flier wire support is securely clamped to the flier body.

3. In a flier for spinning machines and the like, a centrally apertured body member having base and head portions, a frusto-conical shaped

peripheral flier wire support member formed on the body between the base and the head portions, said support member having a peripheral recess in the vicinity of the upper base of the frustum forming a seat for a flier wire, a flier wire support adapted to seat on the peripheral edge of the upper base of the frustum, said support having a central opening adapted to receive the head portion of the body member, a flier wire having a central block engaging section and arms extending outwardly therefrom mounted upon the block, the central block engaging section thereof being seated in the peripheral recess formed in the flier wire support member, and means integral with the flier wire support contiguous to said central opening and frictionally engaging the flier body when the flier wire support is seated in operative position on said peripheral member, whereby the flier wire support is securely clamped to the flier body.

4. In a flier for spinning machines and the like, a centrally apertured body member having base and head portions, a peripheral flier wire support member formed on the body between the base and the head portions, a flier wire support adapted to seat on the peripheral member, said support having a central opening adapted to receive the head portion of the body member, and means integral with the flier wire support contiguous to said central opening, comprising a plurality of tongues formed by slitting portions of the body of the support at spaced points in the vicinity of the opening, said tongues frictionally engaging the flier body when the flier wire support is seated in operative position on said peripheral member, whereby the flier wire support is securely clamped to the flier body.

5. In a flier for spinning machines and the like, a centrally apertured body member having base and head portions, a frusto-conical shaped peripheral flier wire support member formed on the body between the base and the head portions, said support member having a peripheral recess in the vicinity of the upper base of the frustum forming a seat for a flier wire, a flier wire support adapted to seat on the peripheral edge of the upper base of the frustum, said support having a central opening adapted to receive the head portion of the body member, a flier wire having a central block engaging section and arms extending outwardly therefrom mounted upon the block, the central block engaging section thereof being seated in the peripheral recess formed in the flier wire support member, and means integral with the flier wire support contiguous to said central opening, comprising a plurality of tongues formed by slitting portions of the body of the support at spaced points in the vicinity of the opening, said tongues frictionally engaging the flier body when the flier wire support is seated in operative position on said peripheral member, whereby the flier wire support is securely clamped to the flier body.

6. In a flier for spinning machines and the like, a centrally apertured body member having base and head portions, a peripheral flier wire support member formed on the body between the base and head member, a flier wire support adapted to seat on the peripheral member, comprising a cap having a body portion formed with a central opening adapted to receive the head portion of the body member, a pair of depending skirt portions formed on the body of the cap at substantially diametrically opposite points thereof, said skirt portions having flier wire retaining means

formed therein and means integral with said cap contiguous to the central opening and frictionally engaging the flier body when said cap is seated in operative position on said peripheral member, whereby to securely clamp the flier wire support to the flier body.

7. In a flier for spinning machines and the like, a centrally apertured body member having base and head portions, a frusto-conical shaped peripheral flier wire support member formed on the body between the base and the head portions, said support member having a peripheral recess in the vicinity of the upper base of the frustum forming a seat for a flier wire, a flier wire support adapted to seat on the peripheral edge of the upper base of the frustum, comprising a cap having a body portion formed with a central opening adapted to receive the head portion of the body member, a flier wire having a central block engaging section and arms extending outwardly therefrom mounted upon the block, the central block engaging section thereof being seated in the peripheral recess formed in the flier wire support member, a pair of depending skirt portions formed on the body of the cap at substantially diametrically opposite points thereof, said skirt portions having flier wire retaining means formed therein and means integral with said cap, contiguous to the central opening and frictionally engaging the flier body when said cap is seated in operative position on said peripheral member, whereby to securely clamp the flier wire support to the flier body.

8. In a flier for spinning machines and the like, a centrally apertured body member having base and head portions, a peripheral flier wire support member formed on the body between the base and the head portions, a flier wire support adapted to seat on the peripheral member, said support having a central opening adapted to receive the head portion of the body member, means formed on said support for attaching a flier wire thereto, a flier wire having a central block engaging section and arms extending outwardly therefrom mounted upon the block, the arms of the flier wire being in frictional engagement with the attaching means formed on the flier wire support and means integral with the flier wire support contiguous to the central opening frictionally engaging the flier body when the flier wire support is seated in operative position on said peripheral member, whereby the flier wire support is securely clamped to the flier body.

9. In a flier for spinning machines and the like, a centrally apertured body member having base and head portions, a frusto-conical shaped peripheral flier wire support member formed on the body between the base and the head portions, a flier wire support adapted to seat on the peripheral edge of the upper base of the frustum, said support having a central opening adapted to receive the head portion of the body member, means formed on said support for attaching a flier wire thereto, a flier wire having a central block engaging section and arms extending outwardly therefrom mounted upon the block, the arms of the flier wire being in frictional engagement with the attaching means formed on the flier wire support and means integral with the flier wire support contiguous to the central opening frictionally engaging the flier body when the flier wire support is seated in operative position on said peripheral member, whereby the flier wire support is securely clamped to the flier body.

10. In a flier for spinning machines and the like, a central apertured body member having base and head portions, a peripheral flier wire support member formed on the body between the base and the head portions, a flier wire support adapted to seat on the peripheral member, said support having a central opening adapted to receive the head portion of the body member, means formed on said support for attaching a flier wire thereto, a flier wire having a central block engaging section and arms extending outwardly therefrom mounted upon the block, the arms of the flier wire being in frictional engagement with the attaching means formed on the flier wire support and means integral with the flier wire support contiguous to said central opening, comprising a plurality of tongues formed by slitting portions of the body of the support at spaced points in the vicinity of the opening, said tongues frictionally engaging the flier body when the flier wire support is seated in operative position on said peripheral member, whereby the flier wire support is securely clamped to the flier body.

11. In a flier for spinning machines and the like, a centrally apertured body member having base and head portions, a frusto-conical shaped peripheral flier wire support member formed on the body between the base and the head portions, a flier wire support adapted to seat on the peripheral edge of the upper base of the frustum, said support having a central opening adapted to receive the head portion of the body member, means formed on said support for attaching a flier wire thereto, a flier wire having a central block engaging section and arms extending outwardly therefrom mounted upon the block, the arms of the flier wire being in frictional engagement with the attaching means formed on the flier wire support and means integral with the flier wire support contiguous to said central opening comprising a plurality of tongues formed by slitting portions of the body of the support at spaced points in the vicinity of the opening, said tongues frictionally engaging the flier body when the flier wire support is seated in operative position on said peripheral member, whereby the flier wire support is securely clamped to the flier body.

12. In a flier for spinning machines and the like, a centrally apertured body member having base and head portions, a peripheral flier wire support member formed on the body between the base and the head portions, a flier wire support adapted to seat on the peripheral member, comprising a substantially rectangular shaped body portion, having a central opening therein adapted to receive the head portion of the flier block, said body portion being formed with a recess transversely thereof in the vicinity of each of its free ends, each end portion being turned backwardly upon itself in line with the recess to form a slot adapted to receive the arms of a flier wire, and means integral with the flier wire support contiguous to said central opening and frictionally engaging the flier body when the flier wire support is seated in operative position on said peripheral member, whereby the flier wire support is securely clamped to the flier body.

13. In a flier for spinning machines and the like, a centrally apertured body member having base and head portions, a frusto-conical shaped peripheral flier wire support member formed on the body between the base and the head portions, said member having a peripheral recess

5 in the vicinity of the upper base of the frustum forming a seat for a flier wire, a flier wire support adapted to seat on the peripheral edge of the upper base of the frustum, said support comprising a substantially rectangular shaped body portion having a central opening therein adapted to receive the head portion of the flier block, said body portion being formed with a recess transversely thereof in the vicinity of each of its free ends, each end portion being turned backwardly upon itself in line with the recess to form a slot adapted to receive the arms of the flier wires, a pair of flier wires having a central block engaging section and arms extending outwardly therefrom mounted upon the block, the central block engaging section being seated in the peripheral recess formed in the flier wire support member, the arms of the wires overlapping in the vicinity of the block, the portions of the arms therebeyond being seated in the slots formed in the flier wire support, and means integral with the flier wire support contiguous to the central opening, frictionally engaging the flier body when the flier wire support is seated in operative position on said peripheral member, whereby the flier wire support is securely clamped to the flier body.

14. In a flier for spinning machines and the like, a centrally apertured body member having base and head portions, a frusto-conical shaped peripheral flier wire support member formed on the body between the base and the head portions, said support member having a peripheral recess in the vicinity of the upper base of the frustum forming a seat for a flier wire, a flier wire support adapted to seat on the peripheral edge of the upper base of the frustum, said support comprising a substantially rectangular shaped body portion having a central opening therein adapted to receive the head portion of the flier block, said body portion being formed with a recess transversely thereof in the vicinity of each of its free ends, each end portion being turned backwardly upon itself in line with the recess to form a slot adapted to receive the arms of the flier wires, a pair of flier wires having a central block engaging section and arms extending outwardly therefrom mounted upon the block, the central block engaging section being seated in the peripheral recess formed in the flier wire support member, the arms of the wires overlapping in the vicinity of the block, the portions of the arms therebeyond being seated in the slots formed in the flier wire support, and means integral with the flier wire support contiguous to the central opening comprising a plurality of tongues formed by slitting portions of the body of the support at spaced points in the vicinity of the opening, said tongues frictionally engaging the flier body when the flier wire support member is seated in operative position on said peripheral member, whereby the flier wire support is securely clamped to the flier body.
